UNITED STATES PATENT OFFICE.

NAPOLEON GILL, OF HOLYOKE, MASSACHUSETTS, ASSIGNOR OF ONE-THIRD
TO THOMAS W. MANN, OF SAME PLACE.

CUTTING-PLIERS.

SPECIFICATION forming part of Letters Patent No. 316,452, dated April 28, 1885.

Application filed February 21, 1884. Renewed September 22, 1884. (No model.)

To all whom it may concern:

Be it known that I, NAPOLEON GILL, a citizen of the United States, residing at Holyoke, in the county of Hampden and State of Massachusetts, have invented new and useful Improvements in Cutting-Pliers, of which the following is a specification.

This invention relates to improvements in cutting-pliers, the object being to provide an improved tool of this class in which the cutting-jaws are more powerfully actuated than in pliers of ordinary construction, whereby the tool is adapted to cut large metal rods and articles, and also to provide pliers whose cutting-jaws are adapted to be adjusted to open more or less independent of a movement of the handles, and in which the lever-power increases as the jaws approach each other.

In the drawing forming part of this specification is illustrated a pair of pliers embodying my invention.

In the drawing, B is one of the handles of the pliers, having a cutting-jaw, v, thereon, which handle and jaw are made in a similar manner to ordinary pliers, but about at the point on the handle B where the two parts of ordinary pliers are pivoted one to the other is hung the jaw-arm e, so that it may have a vibratory motion. This arm e has formed on its free end the second cutting-jaw, v', whose edge is opposite the aforesaid jaw v. A spring, d, is secured by one end to the outside of the handle B, and extends between that part of the arm e adjoining handle B and the latter, and is bent forward and made to bear on the inner side of arm e to swing jaw v' away from jaw v. Two links, e e, are pivoted by one end at x to the arm e just back of jaw v', one on each side of said arm. The front link is partly broken away to show the second one back of it. The part of the handle B just back of the jaw v passes between the two links e e. The ends of the links e opposite to the pivot x are pivoted to the end of a lever, A, at x² thereon, one end on each side, as on arm e. A screw, w, passes through the lever A, and its lower end is seated in a recess in the curved part of handle B just back of the jaw v, and its rounded point constitutes a fulcrum on

which lever A swings. The screw w is adjustable by turning it in or out, whereby the distance between the jaws v v' is increased or diminished, the lever A being the while in one position.

In using these pliers great cutting-power is obtained, owing to the attachment of the links e e near the jaw v' on arm e, and to the location of the fulcrum-screw w so near the pivot-point x² on lever A, whereby a short lever and a very long one are made to act by approaching lever A and handle B, as shown in dotted lines in the drawing. The dotted lines at the right of the links e and on the lever A show the position of the upper ends of the links e, their pivot x², and the fulcrum-screw w when the long arm of the lever A is brought near to or against the handle B, and when screw w is in the dotted-line position and the pivot x² is swung to a position more nearly over the bearing-point of the screw on handle B the lever-power of lever A is considerably more than before drawing the lever and handle together, and therefore when, in cutting a rather thick bar, the jaws have entered the latter and the greatest cutting resistance comes, the above-named lever, pivot, and fulcrum parts gradually assume positions which in a great measure aid in counteracting the said resistance. If the swing of the arm e on handle B be free, the jaw v' will drop away from jaw v when lever A is moved away from the handle, and under these conditions the spring d may, if desired, be dispensed with.

What I claim as my invention is—

1. Improved cutting-pliers consisting of a handle, B, having thereon one of the cutting-jaws, an arm pivoted to said handle near its jaw, having on its free end the second cutting-jaw, a lever having its fulcrum bearing upon the handle near its jaw, and connected by pivoted links with said pivoted arm, and a spring to swing the jaw of the latter away from the jaw on the handle, combined and operating substantially as set forth.

2. Improved cutting-pliers consisting of a handle, B, having thereon one of the cutting-jaws, an arm pivoted to said handle near its jaw, having on its free end the second cutting-

jaw, a lever having its fulcrum bearing upon the handle near its jaw, and connected by pivoted links with said pivoted arm.

3. Improved cutting-pliers consisting of a handle, B, having thereon one of the cutting-jaws, an arm pivoted to said handle near its jaw, having on its free end the second cutting-jaw, a lever having an adjustable fulcrum, and having its fulcrum bearing upon the handle near its

jaw, and connected by pivoted links with said pivoted arm, and a spring to swing the jaw of the latter away from the jaw on the handle, combined and operating substantially as set forth.

NAPOLEON GILL.
